ATTORNEY.

UNITED STATES PATENT OFFICE

ROY S. ADAMS, OF SAGINAW, MICHIGAN, ASSIGNOR OF ONE-HALF TO JOSEPH PINTO,
OF SAGINAW, MICHIGAN

AUTOMATIC FURNACE REGULATOR

Application filed December 23, 1930. Serial No. 504,337.

The prime object of the invention is to design an automatic temperature control or regulator for automatically opening and closing the draft doors and dampers of a 5 furnace.

Another object is to provide simple, practical, and economical means which can be "set" so that the draft doors and dampers are automatically regulated to maintain an even 10 temperature.

A further object is to provide a regulator which is easy to construct and assemble, which can be readily installed, and which requires little or no attention after installation. 15

With the above and other objects in view, the present invention consists in the combination and arrangement of parts, herein-after more fully described, and illustrated in 20 the accompanying drawing, and particularly pointed out in the appended claims, it being understood that changes may be made in the form, size, proportion, and minor details of construction, without departing from the 25 spirit or sacrificing any of the advantages of the invention.

In the drawing.

Fig. 1 is a front view of a conventional warm air furnace showing my improved regulator in place thereon. 30

Fig. 2 is an enlarged fragmentary part sectional detail of the furnace and regulator.

Fig. 3 is a sectional plan view taken on the line 3—3 of Fig. 2.

Fig. 4 is a front view of one of the sheaves.

Fig. 5 is an enlarged fragmentary view of the control mechanism, showing the manner of adjusting.

Referring now more particularly to the 40 drawing in which I have shown the preferred embodiment of my invention, the numeral 5 indicates a conventional warm air furnace having the usual smoke pipe 6 on which the smoke pipe damper 7 is mounted.

An ash pit door 8 is also provided as usual, and a draft damper 9 forms a part of the said door. 45

The regulating apparatus comprises a cylindrical air drum member 10 which is mounted 50 on and projects into a suitable opening

provided in the warm air jacket 11 of the furnace, the outer end being flanged as shown at 12 to tightly close said opening. A pipe 13 is connected to the head of the drum leading to and communicating with a control tank or container 14, said control tank being formed with inner walls 15 spaced from the outer walls to provide a chamber therebetween, and which is adapted to receive oil or similar liquid 17, the upper end of the 60 inner walls being angled, and an opening 18 is provided for a purpose to be presently described.

Straps 19 are secured to the inner walls of the control tank, or they may be formed integral with the inner walls if desired, a horizontally disposed shaft 20 being journaled therein, and is held in position by means of washers and cotter pins 21 and 21^a respectively. 65

A hollow piston 22 is mounted to float in the control tank 14, the lower end projecting into the oil chamber 16, forming an air tight seal so that air from the tank 10 cannot escape, a centrally disposed clip 23 being provided on the underside of the piston head, and a chain 24 is anchored thereto, the opposite end leading downwardly through the opening 18, and is anchored to a sheave 25 which is mounted on the shaft 20 in any approved manner, a resilient member 26 being provided on the head of the piston, and is adapted to form a stop to limit the upward movement thereof. 75

The outer end of the control shaft is shouldered and threaded as shown at 27, and an indicator 28 is secured thereon by means of the nut 28^a, sheaves 29 and 30 respectively being mounted on the shaft directly adjacent the indicator, the sheave 29 being provided with spaced apart openings 31, which accommodates an inwardly projecting pin member 32, which is anchored in the indicator, one end of a coil spring 33 being anchored to the shaft 20, the opposite end being anchored to the sheave member 30, so that the shaft 20 may be properly tensioned to exert a downward pull on the piston. 85

Stops 34 and 35 are mounted on the respective sheaves 29 and 30, and control chains 36 100

and 37 are also secured thereto, the chain 36 leading over the sheaves 38 and thence leading downwardly and being connected to the draft damper 9 as shown, the chain 37 5 leading over similar sheaves 39, and thence being anchored to the smoke pipe damper 7 in any approved manner, so that, when the draft damper is opened, the smoke pipe damper will be simultaneously closed and 10 vice versa.

In practice the air tight drum 10 is inserted in the warm air jacket as above described, the pipe 13 is connected to the control tank, and as the heat from the furnace heats the 15 tank 10, the air contained therein will be expanded, flowing into the control tank 14 and allowing the piston 22 to move downwardly, the spring then winds the shaft 20 clockwise, rotating the sheaves 29 and 30, so that the 20 smoke pipe damper is opened and the draft damper closed, as the temperature in the warm air jacket is lowered (due to checking the furnace), a partial vacuum is created, this suction causes the piston 22 to move upwardly, consequently the shaft 20 will be rotated counter-clockwise, the stops all brought into engagement, opening the draft damper 9 and closing the smoke pipe damper 7; consequently 25 it will be obvious that an even temperature will be maintained as long as the furnace is supplied with fuel.

It will of course be understood that the control box can be of any desired shape, it may be positioned in one of the rooms of the 35 house if so desired, or it may be an integral part of the tank 10, I find, however, that the arrangement as shown operates very satisfactorily.

The regulator is "set" by rotating the 40 sheave 29, the spring 33 serving to tension the shaft 20 as well as forcing the sheave 29 outwardly and into engagement with the pin member 32, and when it is desired to adjust the regulator, the operator presses inwardly on the sheave 29, compressing the 45 spring 33, this forces the sheave out of engagement with the pin, and if a higher temperature is desired, the sheave is rotated clockwise to a predetermined point, or if a 50 lower temperature is desired the adjustment is identically similar, except that the sheave is rotated counter-clockwise, the spring then forces the sheave outwardly, the pin 32 registering with and engaging one of the openings 55 31, so that the sheave is locked to the indicator.

This mechanism operates accurately and smoothly, insures an even temperature as long as the furnace is fired, it is economical to 60 build, requires no attention after installation, and will last for an indefinite length of time.

What I claim is:—

1. The combination with a furnace, of a drum projecting into the warm air jacket thereof, a control tank communicating there-

with and formed with spaced apart inner and outer walls adapted to form a liquid chamber into which a liquid is introduced, a piston floating in said liquid and adapted to be raised when the furnace temperature is lowered and lowered when the furnace temperature is raised, and means connecting said piston with the furnace draft damper and smoke pipe damper respectively for simultaneously actuating said dampers as the temperature changes. 70

2. The combination with a furnace, of a drum associated therewith and exposed to the heat thereof, a control tank connected thereto and communicating therewith, said tank being formed with spaced apart inner and outer walls adapted to contain a liquid therein, and means mounted to float in said liquid and adapted to be raised when the furnace temperature is lowered and lowered when the furnace temperature is raised for simultaneously opening and closing the furnace draft damper and smoke pipe damper respectively. 80

3. The combination with a furnace, of a drum associated therewith, a control tank connected thereto and communicating therewith, and formed with spaced apart inner and outer walls adapted to contain a liquid therebetween, a piston mounted to float in said liquid and form a seal, said piston being raised when the furnace temperature is lowered, and lowered when the furnace temperature is raised, and means for connecting the furnace draft and smoke pipe dampers to said piston for automatically operating said dampers as the temperature changes. 90

4. The combination with a furnace, of a closed drum exposed to the heat thereof, a control tank connected to and communicating therewith, and formed with spaced apart inner and outer walls adapted to contain a liquid therebetween, a hollow piston telescoping over said inner walls and floating in the liquid to form a seal, said piston being raised when the furnace temperature is lowered, and lowered when the furnace temperature is raised, a chain connected to said piston, and means connecting said chain to the furnace draft and smoke pipe dampers for simultaneously actuating said dampers as the piston is actuated by a change of temperature. 100

5. The combination with a source of heat, of an airtight control member connected to and communicating therewith, said member being formed with spaced apart inner and outer walls forming a liquid chamber therebetween, a piston mounted to float in said member with its lower end projecting into said liquid chamber to form a seal, said piston being actuated by the vacuum or pressure in the control member above the piston, a control shaft, sheaves mounted thereon, and means connecting said piston to said shaft. 110

6. The combination with a source of heat, of a closed drum exposed thereto, a control 120

member communicating therewith, and formed with spaced apart inner and outer walls forming a liquid chamber therebetween, a piston mounted to float in said member with 5 its lower end projecting into said liquid, a spring tensioned control shaft connected to said piston, sheaves mounted thereon, and means for connecting said sheaves to the draft and smoke pipe damper respectively, said 10 piston being raised by the lowering of the temperature of the source of heat.

7. A temperature control comprising a tank formed with spaced apart inner and outer walls forming a liquid chamber therebetween, a piston mounted to float therein, a spring tensioned shaft connected to said piston, means connecting said shaft to the dampers of a furnace, and a closed drum mounted 15 in said furnace and communicating with the upper end of the tank, so that the piston will be raised to open the furnace draft when the 20 furnace temperature is lowered.

In testimony whereof I hereunto affix my signature.
